CLAIM

The ornamental design for a foldable pizza storage container, as shown and described.

DESCRIPTION

FIG. 1 is a top perspective view of a foldable pizza storage container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,

FIG. 9 is a top perspective view thereof shown with the lid in an open configuration.

1 Claim, 9 Drawing Sheets
